UNITED STATES PATENT OFFICE.

ALEXANDER McRAE, OF PENDLETON, OREGON.

GRAIN-SEPARATOR.

No. 820,816.

Specification of Letters Patent.

Patented May 15, 1906.

Application filed February 24, 1904. Serial No. 195,056.

To all whom it may concern:

Be it known that I, ALEXANDER McRAE, residing at Pendleton, in the county of Umatilla and State of Oregon, have invented a new and Improved Grain-Separator, of which the following is a specification.

My invention is embodied in certain improved features of construction, arrangement, and combination of parts, as herein-
10 after described and claimed.

In the accompanying drawings, Figure 1 is a longitudinal section of the grain-separator. Fig. 2 is a side elevation of the same. Fig. 3 is an elevation of the opposite side of the
15 separator. Fig. 4 is an enlarged side view of a portion of the separator frame or casing. Fig. 5 is a detail plan view of the separator. Fig. 6 is an end view of certain parts shown in Fig. 7. Fig. 7 is an enlarged vertical section of the rear part of the grain-cleaner. Fig.
20 8 is a detail view of the large fan, the wind slide and board that coöperate therewith, and the adjusting devices for said slide and board. Fig. 9 is a longitudinal section, and
25 Fig. 10 a cross-section, illustrating the side guides for the endless grain-carrier.

Referring now more particularly to Fig. 1, which illustrates in longitudinal section the general arrangement of the separating mechanism, 71 designates a cylinder of the usual form. 72 72^a indicate flange-pulleys, and 73 an endless rake, hereinafter termed the "straw rattle-rake," which takes around the pulleys 72 72^a and which will be presently
30 again referred to. Disposed below the cylinder is a flange-pulley 74, over which and the sprocket-pulley 75, disposed under and about midway of the rattle-rake, passes an endless chain web 76, by which grain is moved as it is
35 separated from the cylinder and straw-rake to the cleaning mechanism. The said chain web 76 is simply a chain-belt carrier-rake of any well-known construction provided with cross cleats or ribs 76^a, as shown, and the said
40 web or carrier extends up over the arched bottom 77 of the separator, which bottom inclines upwardly and rearwardly and arches in such a manner that the web or carrier 76 is caused to hug the bottom, so that its cross
45 slats or cleats are prevented from riding over the grain and serve in a positive way to convey the grain up over the bottom 77 to the separators presently described. To further hold the chain web or carrier 76 in the proper
50 operative position, sheet-metal slides 78 78^a are provided, one of which, 78, is disposed in

the plane over the separator bottom-section 77, and the other, 78^a, serves as a bottom rest for the upper section of the carrier-web, as shown, the said arrangement of slides 78 78^a 60 being provided to prevent the slats on the carrier-web sliding over the grain, &c. 79, 82, and 89 designate guides over which the straw rattle-rake 73 runs, and 81 designates one of two opposite narrow side flanges or 65 metal strips secured to the sides of the casing and constituting guides for holding the chain web 76 and the rattle-rake apart and from flapping in contact with each other. 82 designates a concaved deck or guide for the 70 rattle-rake, which is disposed beneath a check member 88, disposed transversely over the rattle-rake pendent from the top of the separator-casing, and has for its object to prevent the straw getting between the straw 75 rattle-rake and clogging the same. 83 83^a 83^b designate idler-pulleys over which the straw rattle-rake runs, and the said idler-pulleys also act as a means for creating agitation of the rattle-rake as the same is actuated, which 80 agitation is caused by reason of the cross-slats of the rattle-rake engaging with the said pulleys 83 and other pulleys 86 86^a 90 90^a, or, in other words, by the passage of the cross-slats of the rattle-rake over said pulleys. The lat- 85 ter are mounted rotatably on short journals or stub-axles fixed to the sides of the casing at opposite points. It will be noted in Fig. 1 that the upper and lower runs or halves of the rattle-rake 73 are brought close to each 90 other, and as they also move in opposite directions any grain or straw projecting through the top run of the rattle-rake is struck by the cross-sticks of the lower run thereof and dislodged and spread. This 95 feature, together with the vertical oscillation and agitation of the rake, absolutely prevents clogging of the rake and insures distribution of grain and straw in a most effective manner. The material that is conveyed rear- 100 wardly by the carrier 76 is discharged onto a sieve 113, which extends from the throat 115 of the uppermost fan 114 to the rear or discharge end of the separator-casing, and the said sieve 113 is disposed over another sieve 105 112 in the upper portion of the shoe 122, which is inclined downwardly and forwardly, whereby to discharge the grain received thereon onto the bottom of the shoe 122. The small fan 114 is provided to send the 110 blast through the chute or throat 115, so as to strike the grain and chaff as it falls from

the arched bottom 77. 110 designates the main fan, which discharges into the shoe 122 in the usual manner, its throat or chute 109 being disposed just above the bottom 111 of the shoe 122, as shown, and the casing on the drum of the fan 110 is doubled, as at 110^x, to receive a slide 116, which is controlled by a suitable lever operable from the outside of the separator in the manner presently explained for regulating the blast of the said main fan 110. The conveyer-sieve 113 has an extension 118, which extension has a hinge connection 119 to permit of the member 118 swinging vertically. The chute-bottom or wind-board 109 of the fan is hinged at 120 to the fan-casing to allow for raising or lowering the wind-board, as desired. The adjustable member 118 provides for saving all the grain that would otherwise follow the slope of the bottom of the shoe and be blown over. As shown in Figs. 6 and 7, a flexible fabric 100, preferably canvas, is attached at its upper edge to the rear end 121 of the hinged sieve section 118 and at its lower edge to the box in which the tailings-auger is located. The sieve 118 is hinged at 119. It is expedient that it shall be held inclined upward more or less to hinder the blast from carrying grain off its rear end, and in going up or down grade the inclination should vary correspondingly. To this end I employ means for automatically varying the inclination of the sieve 118, the same consisting of a weight 132, (see Figs. 2 and 7,) attached to the pendent lever-arm 99 of a rock-shaft 99^a, which is journaled horizontally in the casing and has other horizontal arms 99^b, that are connected with the sieve by links 99^c. The oscillation of the pendulum or weight 13 in a vertical plane as the machine inclines longitudinally in passing over undulating or uneven ground serves to raise or lower the sieve accordingly, so that it is maintained at the right inclination. The canvas check 100 obviously prevents escape of the blast below the sieve while thus oscillated vertically and is bellied out by force of the blast, which is curved, returned, or directed upward through the sieve, as indicated by arrows, Fig. 7, and above the sieve such diverted blast or current meets the one flowing over the sieve and interrupts or checks it to such extent as to practically neutralize it, so that there is no force left to carry grain off the rear end of the sieve, and the grain drops through the latter and passes to the conveyer. The shoe 122, which in my construction comprises two shoes in one, has a one-half inch shake and is driven from the fan-shaft in the manner to be hereinafter further explained. 123 designates the conveyer that carries the sieve 113. This conveyer is a grain-board arranged beneath the sieve 113. 87 designates a deck or deflector mounted over the conveyer, by means of which grain that flies upward is re-

turned to the conveyer and saved. 94 designates the grate, which connects with the concave hangers 93 in the usual manner, and 95 is a plate between the concave and the feeder 96, which is in the nature of an endless slatted belt that takes over pulleys 97 98. 108 designates a sluffer-sieve, which is located at the discharge of the shoe-bottom 111 and by which china, lettuce, and heavy stuff are returned to the inclined bottom portion 106, from whence they pass to the second tailings-auger, which is mounted adjacent to and parallel with the grain-auger 103. The recleaner devices include a cockle-screen which receives the grain that passes from the bottom 111 of the shoe over the upper end of the sluffer-sieve 108 and conveys it to the grain-auger 103, and 104 designates the fan for the recleaner mechanism, the chute or throat 105 of which discharges the blast when it strikes against the grain as it falls over the upper onto the lower chute.

Referring now more particularly to Fig. 2, upon the traction-wheel shaft 68 is mounted the large sprocket-wheel 5, which is geared with the sprocket-wheel 40 in the corresponding side of the machine, as shown. 4 designates the sprocket-wheel, mounted on the shaft 2, that carries the sprocket-wheel 45 and which is geared with the sprocket-wheel 21 upon the counter-shaft 3 through chain 21^a. 27 and 27^a designate brackets for supporting portions of the leveling devices, and 200 200^a on Fig. 2 represent brackets that support the worm-gear 7 before referred to. 128 128^a 100 129 129^a designate truss-rods that support the leveling-frame and the rack devices 8. 149 designates a lever-rod device for controlling the dumping-board 150. 28 designates the gear on a cross-shaft 3, before referred to, which imparts motion to the gear 140 on the cylinder-shaft through the medium of the intermediate gears 138 139, and 141 designates a pulley mounted upon the shaft that carries the intermediate gears 138 139 and which, by means of the belt connection shown, imparts motion to the pulley 142 on the feeder-shaft. 103 designates the sprocket-wheel upon the said feeder-shaft, which through the chain belt 143^a engages a sprocket-pulley 144 and 145, which drives the sacker-elevator 146, the grain-auger 143, and the tailings-elevator 147, as also the tailings-auger, from the recleaner 102. 127 designates a post with which the truss-rods 129 129^a and 128 128^a connect and which are also fastened with the main frame, as shown. 130 designates lever-and-ratchet devices for controlling the wind-slide in the main fan-drum, and 160 designates a slot in the side of the separator-casing by which to permit of the adjustment of the said slide. 202 indicates a rod that connects the lever 130 with the wind-slide, and 131 designates a lever-and-ratchet device which through the connecting 130

rod 203 regulates the wind-board, as best shown in Fig. 8. 162 designates the usual grouser attachment for the traction-wheel. 133 designates the pitman which operates 5 the agitator, (shown in detail in Fig. 1,) and 132 designates the weight for regulating the conveyer extension. (Shown in Fig. 1 and in detail in Fig. 7.) 135 135^a designate the shoe-hangers, 134 134^a the conveyer-hangers, and 139 139^a the slots for hangers connection to work under. 153 (see Fig. 2) designates the pulley on the fan-shaft, which through the medium of the belt 155^a connects with the pulley 155, keyed upon the 15 shaft which runs the chain web in the separator (see Fig. 1) and also the tailings-elevator upon the opposite side of the machine from that shown in Fig. 2. 151 designates a pulley on the fan-shaft which drives the 20 rattle straw-rake through the medium of the crossed belt that passes over the pulley 158, and 157 designates the pulley on the fan-shaft which drives the small fan by means of the crossed leather belt that takes over the 25 pulley 156. 154 designates the sprocket upon the drive-shaft 154^a, from which motion is imparted through the medium of the chain belt 154^b to the sprocket 153 and the conveyer. 161 designates the controlling 30 lever-wheel for actuating the disk 17 hereinbefore referred to. 148 designates the sack-ing attachment and hopper, which may be of the ordinary construction. 147 designates the tightener-pulley for the main drive-chain, 35 and 146 the pitman, which is connected to the fan-shaft and which is utilized for actuating the shoe.

Referring now more particularly to Fig. 3, 159 159^a designate slots for the conveyer-hangers 134 134^a to work in. 209 designates the cam-wheel which operates the conveyer by means of the pitman connection 210. In this Fig. 3, 58 designates the pulley upon the counter-shaft 3, which imparts motion to the 45 fan by a leather belt that passes over the fan-pulley 204. 206 designates the main drive-pulley on the cylinder-shaft, which is connected to the fan-shaft by a leather belt on the fan-pulley 205. 207 and 208 designate 50 packer devices of ordinary construction. 211 is a pulley for driving the tailings-elevator 213 to the tailings-auger 101, to which motion is imparted by the leather belt that takes over the said pulley 211 to the pulley 212. 44 designates the oblong eyebolt to which the lowering and raising device is attached. 214 is a rod connection that joins the bolt 44 with the bell-crank lever 215, to which is adjustably connected a rod 218, 55 which joins with the lever 216, disposed adjacent the driver-seat, and which is adapted to coact with the rack 217, the several parts just referred to being provided for adjusting the header-frame.

65 In Fig. 5, 130 131 designate the lever-

ratchet device by which the wind slots and boards are operated from the top of the separator, as hereinbefore referred to.

From the foregoing description, taken in connection with the accompanying drawings, it is believed the construction and the manner of operation of my invention will be readily understood.

By reason of the construction of the parts described the separator commences to separate the grain from the straw under the cylinder and continues such operation the full length of the machine, and by reason of the chain web running over the arched bottom of the separator such arrangement admits of the long separation mentioned and materially assists in the said separation, and, furthermore, by running the web over the arched bottom and by reason of being held in place by slide-guides it does the work perfectly and admits of said long separation, which has heretofore not been possible, so far as I know, in other makes of combined harvesters using aprons.

In its cleaning action my machine has a very large sieve area, and by having three fans which strike the grain as it falls in unbroken blasts through the wind-chutes provided for that purpose the work is done perfectly. By reason of the conveyer adapting 95 itself automatically to the slope of the ground it is impossible to waste grain.

Having thus described my invention, what I claim, and desire to secure by Letters Patent, is—

10c

1. In grain and straw separators, the combination of an endless traveling rake comprising endless webs and transverse slots spaced apart, end rollers or pulleys on which the said rake is supported and travels, side 105 guides over which the upper run of the rake travels, other side guides supporting the lower run of the rake, whereby it is curved upward and inward toward the upper run, the runs thus approximating closely at one 110 point and being somewhat widely separated in front of such point so that grain and straw protruding downward through the upper run at said point are struck by the lower run and carried forward and distributed as specified. 115

2. The combination, with end pulleys, of a traveling rake comprising an endless web and transverse slats attached to its outer side and spaced apart, guides for the upper run of the rake, idler-pulleys arranged under the lower 120 run of the rake and located with reference to the upper guides so as to support the lower run nearer the upper run at one point than any other, the said pulleys thus serving both as guides and means for agitating the lower 125 run as shown and described.

3. The combination, with idler-pulleys, of an endless carrier, composed of an endless belt or web having cross-slats attached to the outer side, pulleys arranged under the lower 130

- run of said carrier and the slats of the latter traveling over the pulleys whereby such lower run is agitated or shaken vertically, as and for the purpose specified.
- 5 4. The combination, with the chain web 76 having cross-slats separated from each other, and end pulleys on which the same runs, of the board 77 having a gradual upward curve and arranged under the lower run 10 of said web so that the slats slide in close contact with the upper side thereof, substantially as described.
5. The combination, with a fan and a grain-conveyer, of a hinged sieve, a flexible 15 check 100 arranged at the end of the grain-winnowing and above said conveyer, and connected with the sieve, and means for automatically supporting and adjusting the outer end of the sieve vertically according to the 20 inclination of the machine in a lengthwise direction, as specified.
6. The combination, with a wheeled frame, casing, and a fan, of a hinged sieve-section 118, and means for automatically adjusting its free outer end vertically, the same consisting of a rock-shaft having a weighted lever-arm and other arms connected with the sieve, the weighted arm being adapted to swing in the direction of the length of the machine, as shown and described. 25
7. The combination, with a fan, a tailings-conveyer, and a hinged sieve having a transverse plate at its outer end, of a canvas check 100 whose upper edge is secured directly to said plate, and a weighted lever operatively 30 connected with the sieve, as and for the purpose specified. 35
